UNITED STATES PATENT OFFICE.

STEPHEN SCANLON, OF NEW YORK, N. Y.

METAL LATH.

1,351,694.

Specification of Letters Patent. Patented Aug. 31, 1920.

Application filed February 4, 1919. Serial No. 275,013.

To all whom it may concern:

Be it known that I, STEPHEN SCANLON, a citizen of the United States, residing at New York, in the county of New York and State of New York, have invented new and useful Improvements in Metal Laths, of which the following is a specification.

This invention relates to new and useful improvements in metal lathing, and has for its primary object to provide a structure of this nature which is of a more or less flexible nature to permit of its adaptability to walls or surfaces of various contours.

A further object of the invention is to provide a metal lath in which attaching means therefor is employed.

A further object of the invention is to provide a device which in addition to its use as a lath, is particularly adaptable to use as a reinforcing means for concrete and analogous structures.

Referring to the drawings:—

Figure 1 is a view in elevation of the lath, Fig. 2 is an edge view thereof,

Fig. 3 is a view showing one of the steps in the process of manufacture of the lath, and

Fig. 4 is a detail sectional view of a portion of the lath.

In forming the lath, a sheet metal blank 10 of rectangular form is employed. This blank 10 is folded at equi-distantly spaced points backwardly upon itself in opposite directions as shown at 11 in Figs. 2 and 3.

After the blank has been thus folded, the same is subjected to pressure under which it is compressed so that the several faces of the folded portions lie in contact with each other as shown in Fig. 3.

With the blank thus folded, it is submitted to the action of suitable rollers to bend the same transversely of the folds as shown at 12 in Fig. 3, thus giving a concavo-convex formation to each of the folded portions.

After this operation, the blank is expand-

ed in any suitable manner as shown in Fig. 2, to provide spaces or pockets 15 between the folds, the walls of which form suitable attaching means for plaster, cement or the like. The bottom wall of each of these pockets is curved as heretofore described as at 12 which forms an additional anchorage for the plastic material which may be applied thereto.

As shown in Fig. 4, the blank is provided at its points of fold with a plurality of apertures which form the means by which the lath is applied to the supporting structure through the medium of nails or the like. These apertures are formed by cutting notches in the edges of the blank when folded as in Fig. 3.

From the foregoing it will be seen that the present invention provides a lath which is readily attachable to a suitable support, and at the same time a lath is formed by which the plastic material for which it is intended to support is firmly locked thereto. Furthermore, a lath constructed in accordance with the present invention is easily expandable to different sizes, thus making it readily adaptable for the purpose designed. The structure is also flexible to a degree to permit of its conforming to irregularities or curves in the surface to which it is applied.

Having thus described the invention, what is claimed is:—

A lath comprising a sheet metal blank folded upon itself at equi-distantly spaced intervals to provide layers contacting throughout their entire area and adapted to be expanded to form oppositely disposed substantially triangular pockets, said pockets tapering inwardly from their outer open ends to provide gradually decreasing opposed upper and lower walls which meet at their inner pointed ends.

In testimony whereof I have affixed my signature.

STEPHEN SCANLON.
